MOP PAIL

William B. Hite, Jr., Webster Groves, Mo., assignor
to Schlueter Manufacturing Company, St.
Louis, Mo., a corporation of Missouri

Application February 10, 1940, Serial No. 318,387

2 Claims. (Cl. 15—262)

This invention relates to a mop pail; and has special reference to an improved wringer device secured to the top of the pail for wringing excess water from a mop during withdrawal thereof from the water within the pail.

An object of the invention is to provide an improved mop wringer pail comprising a rigid frame wholly enclosed within and rigidly attached to the inside of said pail for supporting one of the wringer rollers at the open upper end of the pail, in combination with a frame pivoted to said rigid frame inside the pail for swinging movements and supporting the other one of the two cooperating rollers, a lever attached to said swinging frame inside the pail beyond its axial support from the roller supported thereby and extending above the pail to a position for engagement by the foot of the user to operate said swinging frame, and a platform or foot-rest attached to said swinging frame for receiving pressure to hold the roller supported by said swinging frame in cooperative relation with the roller mounted on the rigid frame.

Other objects and advantages of the invention will be apparent from the following description, reference being made to the annexed drawing, in which—

Fig. 1 is a perspective view of the invention applied to a mop pail.

Fig. 2 is an enlarged vertical sectional view of my improved mop wringer.

Fig. 3 is a plan view of a portion of the device showing the means for preventing the mop from becoming entangled with the roller supports.

The pail 1 may be of any appropriate form and dimensions having a closed bottom and an open top. An ear 2 is rigidly secured to each of two opposite sides of the pail 1, and a bail 3 has its ends pivoted to said ears and may be provided with a rotary handle 4. The bail 3 is of such size that it may swing from downwardly inclined position at either side of the pail upwardly to vertical position to support the pail. As shown in Fig. 1, the bail 3 is in an intermediate position from which it may be swung either upwardly or downwardly.

The frame of my improved mop wringer is rigidly secured within the upper portion of the pail. Said frame comprises two side members 5 connected at one end by an arcuate portion 6 and having arcuate portions 7 at their opposite ends. The portions 6 and 7 seat against the inner surface of the upper margin of the pail and are rigidly attached thereto, thereby supporting the frame side members 5. Thus, the frame parts

6 and 7 reinforce and strengthen the upper margin of the pail and also support the wringer mechanism in connection therewith.

A pair of combined guards and roller supporting brackets are attached to the frame side members 5. Each bracket is preferably composed of sheet metal and includes a part 8 attached to the frame side member 5 and having at its forward end an upwardly extended portion 9 constituting a bearing for the adjacent end of the roller supporting rod 10 on which the roller 11 is mounted. The rod 10 may be rigid with the roller 11 or not, as desired. The ends of the roller 11 are adjacent to the bracket portion 8 which prevents substantial longitudinal movement of the roller. An inwardly extended triangular portion 12 is formed in connection with the lower edge of each bracket portion 8 and is substantially below the lower periphery of the roller 11. A guard wall 13 is formed integral with the lower edge of each flange 12 adjacent to and rearwardly from the roller 11. The walls 13 at opposite sides diverge rearwardly from each other as shown in Fig. 3, the rear ends of said walls being adjacent to the frame side members 5.

A swinging frame comprising a cross member 14 and two forwardly extended arms 15 is pivoted upon an axial support 16 mounted in connection with the opposite ends of the frame side members 5 from the roller axle 10. The roller axle 10 and the rod 16 are parallel with each other. A roller axle 17 is mounted in the forward ends of the arms 15 parallel with the roller axle 10 and supports a roller 18 preferably of about the same dimensions as the roller 11. A foot lever 19 is attached to the cross part 14 approximately at the middle thereof and is of such a length that it may swing downwardly at the inner side of the curved frame part 6 so as to permit the swinging frame to be moved from the position shown in solid lines to the position shown in broken lines in Fig. 2. In the solid line position, the roller 18 is against the roller 11 and supported thereby; and, in the broken line position, the roller 18 is rearwardly beyond the center of gravity so that the swinging frame will remain in an upwardly and rearwardly inclined position until positively moved in the opposite direction beyond the center of gravity.

A foot-rest comprising a knurled or corrugated base 20, a downwardly extended rear flange 21, an upwardly extended front flange or guard 22, and downwardly extended end portions 23, is rigidly attached to the arms 15 of the swinging frame. As shown, the end portions 23 of the

foot-rest are rigidly attached to the outer sides of the arms 15, the flange 21 engages against the upper edges of said arms 15, and the flange or guard 22 rises from the forward edge of the foot-rest 20 a short distance rearwardly beyond the roller 18. The foot-rest 20 is approximately horizontal when the roller 18 is against the roller 11. The formation of the foot-rest with the end flanges 23, the rear downwardly extended flange 21, and the opposite upwardly extended flange 22, provides a rigid connection between the arms 15 and holds said arms in rigid relationship with each other.

The device is used by applying pressure of one foot against the lever 19 to move the swinging frame from the solid line position to the broken line position, leaving an opening between the rollers 11 and 18 through which the mop may be passed into the pail. After the mop has been passed into the pail, the swinging frame is moved forwardly to place the roller 18 against the upper side of the mop. Then pressure is applied upon the foot-rest 20 and the mop is withdrawn between the two rollers, which wring or press excess water from the mop. The guards 13 prevent the mop from becoming entangled at the ends of the rollers 11 and 18.

This invention attains all of its intended objects and purposes efficiently, economically and satisfactorily, and dispenses with the use of pivoted lever connections or other mechanism attached to the outside of the pail. The structure is strong and durable and will withstand all of the stresses and strains for which it is intended, and will last indefinitely. The arrangement and relationship of the parts may be varied within the scope of equivalent limits without departure from the nature and principle thereof.

I claim:

1. In a mop pail having an open top; a frame including two diametrically opposite curved portions fitting against the inner surface of the upper margin of the pail and rigidly attached thereto, and two approximately parallel side members integrally connecting said curved por-

tions; a roller supported by said side portions for rotation about a horizontal axis partially within the upper end of the pail; a pair of arms pivotally supported by said side portions within and near the opposite side of the pail from said roller and connected by a base member; a second roller rotatively supported by said arms about a horizontal axis parallel with the axis of said first roller; and a foot lever attached to said base member between said side portions and inwardly from the adjacent curved portion of said frame and extending upwardly above the upper end of the pail for swinging movements downwardly within the pail to move said arms and thereby said second roller upwardly away from said first roller.

2. In a mop pail having an open top; a frame including two opposite curved portions fitting against and rigidly attached to the inner surface of the upper margin of the pail, and two approximately parallel side members rigidly connecting said curved portions; a roller supported by said side portions for rotation about a horizontal axis near one of said curved portions; guard elements attached to said side members within the pail and converging from said side members toward said roller to prevent mop material from becoming entangled at the ends of said roller; a pair of arms pivotally supported by said side portions near the opposite side of the pail; a second roller rotatively supported by said arms about an axis parallel with the axis of said first roller; a part rigidly connecting said arms adjacent to the pivots supporting them; a foot lever attached to said part and extending upwardly above the upper end of the pail for swinging movements downwardly within the pail between said part and the adjacent curved portion of said frame to move said arms and thereby said second roller upwardly away from said first roller; and a bail pivoted to the opposite sides of said pail for upward and downward swinging movements when said rollers are in contact with each other.

WILLIAM B. HITE, JR.
